(57) **CLAIM**

The ornamental design for a scooter interface device, as shown and described.

DESCRIPTION

FIG. 1 is a front perspective view of the hardware module of the scooter interface device showing our design;

FIG. 2 is a rear perspective view thereof;

FIG. 3 is a front-facing view thereof;

FIG. 4 is a back-facing view thereof;

FIG. 5 is a left-facing view thereof; and,

FIG. 6 is a right-facing view thereof.

The broken lines represent the environment in which the scooter interface device resides and forms no part of the claimed design.
